UNITED STATES PATENT OFFICE

161,028

DISINFECTING GARBAGE CONTAINER

Eugene Levin, Dallas, Tex.

Application May 10, 1949, Serial No. 2,554

Term of patent 14 years

(Cl. D58—17)

To all whom it may concern:

Be it known that I, Eugene Levin, a citizen of the United States, residing at Dallas, in the county of Dallas and State of Texas, have invented a new, original, and ornamental Design for a Disinfecting Garbage Container, of which the following is a specification, reference being had to the accompanying drawing, forming a part hereof.

In the drawing:

Figure 1 is a side elevational view of a disinfecting garbage container, showing my new design; and

Figure 2 is an exploded perspective view thereof.

I claim:

The ornamental design for a disinfecting garbage container, as shown.

EUGENE LEVIN.
